UNITED STATES PATENT OFFICE

ORVILLE U. DESHA, OF FORT COLLINS, COLORADO, ASSIGNOR OF ONE-FIFTH TO THE
DESHA TYPELEX TRUST ESTATE, OF FORT COLLINS, COLORADO

KEY ACTION FOR TYPEWRITERS AND OTHER MACHINES

Application filed January 27, 1928. Serial No. 249,881.

In regard to certain more specific features thereof, my invention relates to improvements in the associated and coacting parts of a key mechanism of a machine whose actuating means operatively connecting the type bar and key lever move the type bar to printing point upon depression of the key lever; said connection embodying coacting means reversely breaking the said connection after the printing impact of the type bar for the return of the type bar to its normal position while the key lever is in depressed position; and also including coacting means for restoring said connection to normal operative position upon release of the key lever; this broad object being the subject matter of an application filed by me on November 5th, 1923, Serial No. 672,871, upon which Patent 1,643,203 issued Sept. 20, 1927, as a contradistinction between previous devices comprising a detachable connection or gap at some point between the key lever and type bar after the latter has been given the movement necessary to effect the printing and before the key lever has completed its cycle of movement.

Among the objects of the present invention, the applicant has endeavored: First, to improve the coacting parts between the key lever and type bar which will provide, among other features, a key action which will be efficient in use, rapid and reliable in operation, and which shall have a light touch for operating the type bar, and reduce the liability of the type to collide or "pile" when operated at high speed. Second, to provide a key mechanism of the above character having few parts simple in construction which will be cheap to manufacture, convenient and easy to arrange and assemble compactly, and construct a key mechanism as to be but little likely to get out of order in usual operation.

My invention, accordingly, consists in certain combinations of elements, features of construction, and arrangement of parts, that may readily be incorporated in certain typewriting machines with only slight modification of the structural features of said machines as they now exist, exemplified in the construction hereinafter set forth, which will

be more readily understood from an inspection of the accompanying two sheets of drawings and the following specifications, the scope of the invention being indicated in the appended claims.

My invention is especially applicable to the usual hand operating machine, as distinguished from a motor driven machine, and is shown in the present case embodied in a machine similar to the Remington standard typewriter. It should be understood, however, that the invention is not restricted to use in a machine of this type, but may be employed wherever found available.

The applicant has endeavored to disclose and describe the construction of the mechanism and manner of its operation and its use in language comprehensible to those versed or skilled in the art who would make or use the device, sufficient to satisfy the requisites of this application, without enumerating every obvious object and advantage, or pointing out all the difficulties and troubles which are cured or ameliorated by his improvement over the present state of the art, the following being a brief description of the several views of the drawings: Fig. I is a sectional elevation of a typewriting machine taken longitudinally and about centrally thereof, constructed in accordance with my invention and showing elements of one key action only in normal position, and also showing so much of the usual mechanism of the machine as is necessary to illustrate how my invention may be embodied therein. Fig. II, represents a view of the key action similar to Fig. I, the key lever being shown depressed and responding the type bar. Fig. III is a key mechanism similar to Fig. I the key lever being shown in a depressed position and the type bar responded to printing position. Fig. IV is also a key mechanism similar to Fig. I, the key lever being shown in a depressed position and the type bar returned to its initial position. In this manner the key lever may be held down to its limit of movement and the type bar will complete its incident of response to effect the printing and move out of engagement with the platen and complete its cycle of movement regardless of

whether or not the key lever is released, thus relieving the key lever of work during the impact printing operation.

The following detailed description sets forth the best mode in which the applicant has contemplated applying the invention. It is understood, of course, that for the sake of clearness and to avoid complication of drawings elements of the complete machine already known to the art, constituting no part of the present invention, and statements of mere obvious facts, are omitted. In the accompanying drawings similar reference characters indicate corresponding parts in the several views, and in order to facilitate observance of a clear distinction between this and copending applications, the reference characters also indicate as far as practical, the corresponding parts in the several views of my copending applications, Serial No. 55,227 filed September 8, 1925, and Serial Nos. 178,083, 178,084, 178,085, 178,086, 178,087, 178,088, and 178,089 filed March 24, 1927. In the embodiment in Fig. I, more in detail, in which one form of type action is shown as applied to a typewriting machine to which it is particularly adapted, 1 indicates the typewriter frame—1^a indicating the front and 1^b the rear. 5 indicates a common platen mounted as usual to travel longitudinally across the rear upper portion of the machine upon a carriage mechanism. As the carriage mechanism forms no part of the present invention, specific disclosure and description thereof is omitted, as its broad function is well known. 6 indicates one of a series of type bars each carrying at its front end type 7 and provided at its rear end with operative pin and slot connection 8 and 8^a said type bars being radially arranged in a curved row about the same center and are movable about their fulcrum pivot rod 9 on a type bar segment 10, Fig. I, from a horizontal or forwardly extending radial position E on cushion rest 11 forming the arc of vibration G and is brought against the front face of platen 5 to a common printing point A, to an upright radial position as shown by radius F. 12 indicates one of a series of key levers providing an upward arm 12^a intermediately of its ends and carrying at the front end finger key 13, the rear end pivoted at 14 supported by bar 14^a in the rear of the machine, and is kept normally in its elevated position by the usual spring 15 supported by said bar 14^a at normal rest the key lever bearing against the underside 15^a of the buffer bar for the key lever 12. 18 indicates one of a series of vibratory levers corresponding in number with the type bars 6 and key levers 12 pivoted intermediately of its ends at 19 supported by bar 20. Means operatively connecting the type bar and vibratory lever may be that of any well known in the art but preferably the usual pin and slot connection

8 and 8^a at the heel of the rear end of the type bar and upper end of the vibratory lever. 21 is an actuating trip link pivoted at 21^a to the lower end of the depending arm of the vibratory lever and is provided with an eccentric slot 21^b engaging the actuating tripper pin 22 supported by the key lever arm. The actuating trip link 21 provides a shoulder or an interlocking hump projecting within said slot operatively interlocking the pin 22 carried by the key lever arm. The elements 21 and 22 therefore provide a reversely breaking actuating coupling for moving the type bar to printing point upon depression of the key lever.

The new mechanical structure, combination of parts and operation thereof are the important factors of the invention in providing the desired function of the key action, a further description of the operative principle, therefore, follows:

The key lever 12 is described as having two incidents of operation before completing its operative cycle, namely: the incident of depression and the incident of release. The incident of depression is disclosed by the movement of the key lever 12 from radius B to radius C, and the incident of release is disclosed by the movement of the key lever 12 back from radius C to radius B. The type bar 6 is described as having two incidents of operation, before completing its operative cycle, namely: incident of response and incident of recoil. The incident of response of the type bar 6 is disclosed by the movement of the type bar from its initial rest radius E to printing point A, at radius F, forming arc G from pivot 9. The incident of recoil of type bar 6 is disclosed by its movement from the printing point A back to normal rest E thereby completing its operative cycle. These incidents of operation are, of course, common in nonreversely breaking type bar actions in so far as the incident of response, E to A, of the type bar 6 occurs simultaneously with the incident of depression, B to C, of the key lever 12, and the incident of recoil, A to E, of the type bar occurs simultaneously with the incident of release, C to B, of the key lever. In other words, the operative cycle of the type bar and that of the key lever are simultaneous in a nonreversely breaking connection, but the broad function inherent to the present key action relative to the correlation of incidents of operation of the key lever with that of the type bar is in providing the operative expedient by which both the incident of response, E to A, of the type bar and the incident of recoil, A to E, occur during the one incident of depression, B to C, of the key lever, the type bar completing its operative cycle while the operative cycle of the key lever is only half complete. Upon depression of the key lever the actuating tripper pin 21^b moves

downwardly carrying with it the forward end of the trip link 21 the latter being operatively interlocked with backward thrust moves the depending arm of the vibratory lever backwardly vibrating the latter and in turn operates the type bar from radius E to about radius E^a, Fig. II. 23 is a trip dog loosely mounted on said vibratory lever pivot rod beside its vibratory lever, its forward end is provided with a trip nose communicating with the rear edge of the trip link 21 as shown in Fig. I; and upon depression of the key lever and rear end of the trip dog 23 communicates with the stop rod 24 supported by bar 20 reversely breaking the trip elements after printing impact of the type bar 6 for returning the latter to normal position of rest while the key lever is held in depressed position as shown in Fig. IV.

It is equally important that reliable and rapid means be provided for restoring the elements 21 and 22 of the reversely breaking actuating coupling to normal operative position upon release of the key lever, this expedient is accomplished by the return plate 25 loosely pivoted at 25^a intermediately of its ends to the side of the key lever 12, and is provided with a return hammer 25^b at its forward end. Upon release of the key lever the rear end of the return plate 25 communicates with a set screw 26 supported by bar 20 turning the return plate on its pivot 25^a causing its forward return hammer to communicate with the lower edge of the trip link 21 and in turn moves the latter to its normal interlocked position with the actuating trippet pin 22.

Finally, it will be seen that the present invention provides a simple and practical type action which will be rapid and efficient in use, accomplishing, among others, all of the objects and advantages above set forth, therefore the operation and method of use of a type action of this character is believed to be perfectly clear from the above description, a reiteration thereof is believed to be unnecessary. As many changes could be made in the above construction and many apparently widely different embodiments of this invention could be made without departing from the scope thereof and it is intended that all matter contained in the above description or shown in the accompanying drawings, shall be interpreted as illustrative and not in a limiting sense, and variations may be resorted to within the scope of the invention, and portions of the improvement may be used without others.

Having described my invention, what I claim as new and desire to secure by Letters Patent is:

1. In a typewriter key action, a type bar, a key lever providing an upward arm intermediately of its ends, a vibratory lever pivoted

intermediately of its ends, means operatively connecting the upward end of the vibratory lever with the type bar, an actuating trip link operatively connected to the lower end of the vibratory lever, an actuating trippet pin carried by said key lever arm operatively interlocking the actuating trip link moving the type bar to printing point upon depression of the key lever, means disinterlocking said trippet pin and actuating trip link for returning the type bar to normal position while the key lever is in depressed position.

2. In a typewriter key action, a type bar, a key lever providing an upward arm intermediately of its ends, a vibratory lever pivoted intermediately of its ends, means operatively connecting the upward end of the vibratory lever with the type bar, an actuating trip link operatively connected to the lower end of the vibratory lever, an actuating trippet pin carried by said key lever arm operatively interlocking the actuating trip link moving the type bar to printing point upon depression of the key lever, means disinterlocking said trippet pin and actuating trip link for returning the type bar to normal position while the key lever is in depressed position, means restoring said actuating trip link and trippet pin to normal interlocked position upon release of the key lever.

3. In a key action, a type bar, a key lever providing an upward arm intermediately of its ends, a vibratory lever pivoted intermediately of its ends, means operatively connecting the upward end of the vibratory lever with the type bar, an actuating trip link operatively connected to the lower end of the vibratory lever, the actuating trip link having an eccentric slot, an interlocking hump projecting within said slot, an actuating trippet pin carried by said key lever arm engaged within the forward end of said slot in front of said interlocking hump operatively interlocking said actuating trip link moving the type bar to printing point upon depression of the key lever, means disinterlocking said trippet pin and actuating trip link moving said pin to the rear end of said slot behind said interlocking hump for returning the type bar to normal position while key lever is in depressed position.

4. In a typewriting machine, a type bar, a key lever providing an upward arm intermediately of its ends, a vibratory lever pivoted intermediately of its ends, means operatively connecting the upward end of the vibratory lever with the type bar, an actuating trip link operatively connected to the lower end of the vibratory lever, the actuating trip link having an eccentric slot, an interlocking hump projecting within said slot, an actuating trippet pin carried by said key lever arm engaged within the forward end of said slot in front of said interlocking hump operatively inter-

locking said actuating trip link moving the type bar to printing point upon depression of the key lever, means disinterlocking said trip-
pet pin and actuating trip link moving said 5 pin to the rear end of said slot behind said interlocking hump for returning the type bar to normal position while the key lever is in depressed position, means restoring said trip-
pet pin to normal operative position within 10 the forward end of said slot in front of said interlocking hump upon release of the key lever.

5. In a typewriting machine, a type bar, a key lever providing an upward arm inter-
mediately of its ends, a vibratory lever, a supporting bar extending across the machine above the key lever supporting a pivot rod for said vibratory lever intermediately the ends of the latter, means operatively connect-
ing the upward end of the vibratory lever 15 with the type bar, an actuating trip link operatively connected to the lower end of the vibratory lever, an actuating trippet pin carried by said key lever arm operatively interlocking the actuating trip link moving the type bar to printing point upon depression of the key lever, a trip rod carried by said vibratory lever supporting bar in the rear of said vibratory lever pivot, a trip dog loosely mounted 20 on said vibratory lever pivot rod beside its vibratory lever and its rear end communicat-
ing with said trip rod, a trip nose provided by the forward end of said trip dog com-
municating with the rear edge of the trip link 25 disinterlocking the actuating trip link for returning the type bar to normal position while the key lever is in depressed position.

6. In a type key action, a type bar, a key lever providing an upward arm intermediate-
ly of its ends, a vibratory lever, a support-
ing bar extending across the machine above 30 the key lever supporting a pivot rod for said vibratory lever intermediately the ends of the latter, means operatively connecting the up-
ward end of the vibratory lever with the type bar, an actuating trip link, operatively connected to the lower end of the vibratory lever, an actuating trippet pin carried by said key lever arm operatively interlocking the 35 actuating trip link moving the type bar to printing point upon depression of the key lever, a trip rod carried by said vibratory lever supporting bar in the rear of said vibratory lever pivot, a trip dog loosely mounted 40 on said vibratory lever pivot rod beside its vibratory lever, and its rear end communicat-
ing with said trip rod, a trip nose provided by the forward end of said trip dog com-
municating with the rear edge of the trip link 45 disinterlocking the actuating trip link for returning the type bar to normal position while the key lever is in depressed position, means restoring said actuating trip link and trippet pin to normal interlocked position upon re-
lease of the key lever.

7. In a key action for a typewriting ma-
chine, a type bar, a key lever providing an up-
ward arm intermediately of its ends, a vibratory lever, a supporting bar extending across 50 the machine supporting the pivot rod for said vibratory lever intermediately the ends of the latter, means operatively connecting the upward end of the vibratory lever with the type bar, an actuating trip link operatively connected to the lower end of the vibratory lever, an actuating trippet pin carried by said key lever arm operatively interlocking the actuating trip link moving the type bar to printing point upon depression of the key lever, means disinterlocking said trippet pin 55 and actuating trip link for returning the type bar to normal position while the key lever is in depressed position, a return plate loosely pivoted to the side of the key lever, a set screw supported by the vibratory lever supporting bar communicating at the rear end of said return plate, a return hammer provided at the forward end of said return plate communicating with the lower edge of the trip link moving the latter to its normal 60 interlocked position with the actuating trippet pin upon release of the key lever.

8. In a typewriter key, in combination, a type bar, a key lever pivoted at its rear end and providing an upward arm intermediate-
ly of its ends, a vibratory lever, a support-
ing bar extending across the machine above 65 the key lever supporting a pivot rod for said vibratory lever intermediately the ends of the latter, means operatively connecting the upward end of the vibratory lever with the type bar, an actuating trip link operatively connected to the lower end of the vibratory lever, the actuating trip link having an ec-
centric slot, an interlocking hump project-
ing within said slot, an actuating trippet pin 70 carried by said key lever arm engaged within the forward end of said slot in front of said interlocking hump operatively interlocking the actuating trip link moving the type bar to printing point upon depression of the key lever, a trip rod carried by said vibratory lever supporting bar in the rear of said vibratory lever pivot, a trip dog loosely mounted 75 on said vibratory lever pivot rod beside its vibratory lever and its rear end communicat-
ing with said trip rod, a trip nose provided by the forward end of said trip dog com-
municating with the rear edge of the trip link 80 disinterlocking the actuating trip link for returning the type bar to normal position while the key lever is in depressed position, a return plate loosely pivoted to the side of the key lever, a set screw supported by the vibratory lever supporting bar communicat-
ing at the rear end of said return plate, a re-
turn hammer provided at the forward end 85 of said return plate communicating with the lower edge of the trip link moving the lat- 90

ter to its normal interlocked position with the actuating trippet pin upon release of the key lever.

Signed at Fort Collins, in the county of Larimer and State of Colorado, this 28 day of January, A. D. 1928.
